INVENTOR:
WILLIAM D. DAVIDSON,
BY F. M. Flavin

ATTORNEY.

UNITED STATES PATENT OFFICE

WILLIAM D. DAVIDSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

KELLY BUSHING

Application filed March 28, 1932. Serial No. 601,558.

My invention relates to a kelly bushing for use in providing a driving connection between the rotary table of a rotary machine and the kelly or drill stem of a string of drill pipe, these elements being well known in the oil well drilling industry.

In order that the advantages and objects of my invention may be better understood I will briefly refer to that part of the oil-producing industry to which my invention appertains. In the drilling of an oil well it is common practice to set up a derrick and to place on the floor of the derrick a rotary machine having a rotary table through which the drill pipe is extended. The lower end of the drill pipe has a bit provided thereon whereby the well is drilled. The drill pipe is supported by a suitable travelling block by means of which it is fed downwardly as drilling progresses. The uppermost part of the drill pipe is ordinarily provided in the form of a drill stem or kelly which is rectangular in outer cross-section in order that gripping engagement may be had therewith in order that the drill stem or kelly may be driven by the rotary machine. At the present time it is common practice to provide the kelly bushing in the form of two parts which are set into a suitably shaped socket provided in the rotary table around the opening through which the drill stem is passed. The kelly bushing ordinarily employed in the drilling art has flat faces adapted to be engaged by the flat faces of the drill stem or kelly. When the rotary table is rotated the kelly bushing is rotated therewith and by reason of the interengagement between the flat faces, the drill stem and the drill pipe secured thereto are rotated. During the drilling operation the travelling block which supports the drill pipe is lowered in order that the bit secured to the lower end of the drill pipe can move downwardly as drilling operations are continued.

It is an object of my invention to provide a kelly bushing which has a body in one-piece and which at all times remains on the kelly or drill stem. It is unnecessary in my invention to remove the kelly bushing from the drill stem and it is unnecessary to separately

remove the kelly bushing from the rotary machine, this being automatically taken care of by a raising of the drill pipe. This occurs due to the fact that at the lower end of the drill stem there is a tool joint for connecting the drill stem to the other section of the drill pipe. This tool joint is of larger cross-sectional area than the drill stem and thus provides a shoulder which engages the kelly bushing upon upward movement of the column of drill pipe, thus removing the kelly bushing from the rotary table.

It is another object of my invention to provide a kelly bushing of the character mentioned in which slips are provided which may be interchanged to suit different sizes of drill stems. It is, therefore, possible by the use of my invention to use the kelly bushing on different sizes of drill stems merely by exchanging one set of slips for another.

During the operation of the well drilling apparatus just described the torque transmitted from the rotary table to the drill stem is transmitted through the flat faces of the slips of the kelly bushing and the flat faces of the drill stem. Due to the fact that the rotation of the rotary machine is in one direction, the torque is transmitted from the kelly bushing to the drill stem only along one edge or along one side of each slip and each face of the drill stem, with the result that the wear does not take place evenly but only on one side of the interengaging faces. As this wear continues there will be a noticeable play between the kelly bushing and the drill stem with the result that when the apparatus is started and stopped there will be a severe pounding action as the faces of the slips of the kelly bushing come into engagement with the faces of the drill stem. It is an object of my invention to provide a kelly bushing in which the slips may be inverted in order that the worn portions thereof will be moved into such positions that they are not engaged by the faces of the drill stem and so that the unworn portions of the slips may be brought into working position.

It is a still further object of my invention to provide a kelly bushing which is very economical to manufacture and which may there-

fore be supplied to the oil drilling industry at a relatively low cost. My invention includes various refinements of construction whereby the machining is reduced to a minimum in order that the cost of production will be very low. These details of construction will be fully pointed out in the detailed description of my invention to follow.

It is a still further object of my invention to provide a novel construction whereby the slips may be removably held in place so that they may at the same time be rigidly clamped to the body of the kelly bushing in order that the assembly will have the necessary strength.

Other objects of my invention reside in the details of construction which are conducive to simplicity and economy. These other objects and advantages of my invention will appear in the following description.

Referring to the drawings:

Fig. 1 is an elevational view illustrating the utility of my invention.

Fig. 2 is a plan view partly in section, taken as indicated by the line 2—2 of Fig. 1.

Fig. 3 is a section taken on the line 3—3 of Fig. 2.

Fig. 4 is a bottom plan view of the kelly bushing of my invention.

Fig. 5 is a plan view showing a partial assembly of the parts of my invention.

Fig. 6 is a sectional view showing the parts in separated position and disclosing the manner in which they are assembled on the kelly or drill stem.

Referring to the drawings and particularly to Fig. 1, the numeral 11 represents the kelly bushing of my invention which is adapted to be supported by a table 12 of a rotary machine 13. Extending through the kelly bushing 11 is a kelly or drill stem 15 which is rotated. The drill stem 15 forms the upper part of the string of drill pipe 16 which is supported by a travelling block 17 and which is provided at its lower end with a drill bit 18.

The kelly bushing is best shown in Figs. 2 to 5 inclusive, and in order that the details of construction of my invention may be fully understood, reference will now be had to these views.

The kelly bushing includes a cast body 20 which is so designed that there will be but a minimum of machine work required. The body 20 is cast with a somewhat cylindrical portion 21 at the lower end of which there is formed a block portion 22 having vertical faces 23 and lower horizontal faces 24 which are suitably machined for reception in a socket 26 provided in the rotary table 12. Formed below the block 22 is an extension 27 of general cylindrical form having an outer conical face 28 which is adapted to rest in a similarly shaped opening provided in the rotary table 12. The body 20 has a cored recess or channel 31 formed on the interior thereof, preferably in the block 22, which cored recess 31 is in

communication with a passage 30 shown in the drawing.

The body has a cylindrical face 33 which extends from the upper end of the body to a point below the cored recess 31, terminating at a shoulder means provided in the form of four inwardly extending shoulders 34. Formed on the interior of the body from the upper end thereof downwardly or inwardly to the cored recess 31 is a plurality of longitudinal channels 35 which are spaced apart a distance of 90°. These channels have flat bottom faces 36 and side faces 37 which extend at right angles to the bottom face 36. These channels 35, therefore, may be very easily cut, there being no undercutting or dovetailing required. The cored recess 31 not only reduces the weight of the drill kelly but also renders the milling of the channels 35 a very simple matter, since it is not necessary to stop the milling operation at a given point. The slots are milled from the upper end of the body and downwardly to the cored recess.

Adapted to be placed in the body in contact with the shoulders 34 is a retaining means in the form of a retaining ring 38. This ring 38 has an inwardly and upwardly extending ledge 39 having an outer upwardly and inwardly extending conical face 40 and a flat face 41, as shown. The purpose of this retaining ring 38 is to retain in place the lower ends of keys 43 and slips 44.

The keys 43 have rectangular portions 45 at rest in the channels 35. Projecting inwardly from each rectangular portion 45 is a triangular portion 46 having faces 47 which extend at an angle of 90° to each other, this angle being bisected by a radial line which extends outwardly from the axis of the body 20 and centrally through the key 43. The triangular portion 46 extends outwardly below the rectangular portion 45 and the lower end thereof is provided with an inclined or beveled face 48 which engages the conical face 40 of the retaining ring 38. It will be seen that the interengagement between the faces 40 and 48 will retain the lower ends of the keys 43 in place. The upper ends of the keys 43 are provided with arcuated beveled faces 49. Adapted to be secured to the upper end of the body 20 is a cover 51 having downwardly extending studs 52 which project through ears 53 provided at the upper end of the body 20. Nuts 54 are advanced on the lower ends of the studs for securing the cover in place. The cover is held in a centralized position by means of a downwardly extending annular projection 55 which surrounds an annular extension 56 formed at the upper end of the body 20. The cover 51 has a central opening 57, and surrounding the opening 57 is a downwardly projecting portion 58 which has a conical face 59 adapted to engage the bevelled faces 130

49 of the keys 43, thus retaining the upper ends thereof in place.

Placed between each key 43 in the opening 30 is one of the slips 44. Each slip 44 has an outer cylindrical face 60 adapted to engage the cylindrical face 33 of the opening 30. Each slip has side faces 61 adapted to engage the faces 47 of the keys 43 and has an inner flat face 62 which extends perpendicular to a radial line extending from the axis of the body 20 through the central part of the slip. When the four slips 44 are positioned as shown in Fig. 2 the faces 62 co-operate to provide a rectangular passage 63 for receiving the drill stem 15. The drill stem 15 as shown clearly in Fig. 2 has four flat faces 64, each of which is adapted to engage one of the flat faces 62 of the slips 44.

The lower ends of the slips 44 are provided with arcuated projections 66 having inner inclined faces 67 adapted to engage the outer bevelled face 40 of the retaining ring 38, thereby holding the lower ends of the slips 44 in place. The upper ends of the slips are provided with arcuated projections 68 having inner inclined faces 69 which are adapted to engage the bevelled face 59 of the projection 58 of the cover 51. In this manner the upper ends of the slips are retained in place.

It will be seen that but a minimum of machine work is required on the body. The cylindrical face 33 may be very easily turned and the longitudinal channels 35 may be economically formed, due to the fact that the side walls 37 thereof are parallel. In Fig. 5 I have shown a plan view of the parts of my invention partly assembled. This view clearly shows the shape of the interior opening through the body 20.

In Fig. 6 I show the manner in which the parts are assembled. The body 20 is extended over the drill stem 15 with the retaining ring 38 in place. The cover 51 is likewise placed on the drill stem 15 and is supported in a position spaced away from the body 20, as shown. The keys 43 are next installed in place, after which the slips 44 are installed in place. The lower ends of the keys and slips are retained against the body by means of the retaining ring 38. After these parts have been assembled the cover 51 is then lowered into place and the nuts 54 are advanced onto the studs 52, thus completing the assembly and thus securely locking the removable parts to the body. It will be seen that the parts are easily slipped into place due to the fact that the assembling operation is performed around the drill stem 15. The drill stem 15, therefore, guides the lower ends of the keys 43 and the slips 44 into place. For the convenience of handling the various removable parts threaded openings 73 are provided in the opposite ends of the keys and

slips in order that a handling device 74 may be employed.

When once the kelly bushing is installed on the kelly or drill stem 15 it is not necessary that it be removed. The kelly bushing occupies a position as shown in Fig. 1. The interengagement between the faces 62 of the slips 44 and the faces 64 of the kelly bushing 15 provides the driving engagement which rotates the drill pipe. Since these interengaging faces are flat the drill pipe may be lowered or raised, as desired, during the drilling operation. When the drill pipe has been lowered to such an extent that the upper end of the drill stem is immediately above the kelly bushing it will then be necessary to raise the drill pipe and add another length of pipe thereto. When the drill pipe is raised, the tool joint identified by the numeral 75 which connects the drill stem to the adjacent drill pipe of the string of drill pipe 16 will engage the kelly bushing and remove it from the cavity 26 of the rotary table 12. After the length of drill pipe has been installed and suitably connected to the drill stem 15 the parts are then lowered and the kelly bushing may be guided into the cavity 26 of the rotary table 12 so that drilling operations may be continued.

During drilling operations the parts rotate in a direction indicated by the arrow 76 of Fig. 2. This causes the complementary faces 62 and 64 to be in engagement along one edge at points indicated at 77. All of the wear, therefore, between the faces occurs at the portions of the faces 62 and 64 indicated by the numeral 77, and no wear occurs along the opposite portions of these faces. When wear occurs to such an extent that there is an undesirable play it is possible to remove the cover and remove and invert the slips, thus bringing the unworn portions of the faces 62 into positions where they will be engaged by the faces 64 of the drill stem 15.

The device which I have described in detail accomplishes all of the objects of my invention. The details of design are those which I prefer to use. It should be strictly understood, however, that I do not wish to be limited to the exact details of construction which I have disclosed as being preferable, since the predominating features and principles of my invention may be incorporated in various physical embodiments. I desire to have my invention construed by the appended claims.

I claim as my invention:

1. In a kelly bushing for use in establishing a driving connection between a rotary table and a drill stem, the combination of: a body having a block portion for engagement with said rotary table, there being an opening therethrough; a plurality of slips disposed in said opening; retaining means at the lower ends of said slips; and a cover

secured to the upper end of said body for immovably securing the upper ends of said slips to said body.

2. In a kelly bushing for use in establishing a driving connection between a rotary table and a drill stem, the combination of: a body having a block portion for engagement with said rotary table, there being an opening through said body; shoulder means in said opening, and there being longitudinal channels in said body in communication with said opening; a retaining ring placed in said opening in contact with said shoulder means; keys disposed in said channels and extending into said opening, the inner ends of said keys engaging said retaining ring; a cover secured to an end of said body and holding said keys in said body; and slips disposed in said opening between said keys.

3. In a kelly bushing for use in establishing a driving connection between a rotary table and a drill stem, the combination of: a body having a block portion for engagement with said rotary table, there being an opening through said body; shoulder means in said opening, there being longitudinal channels in said body in communication with said opening; a retaining ring placed in said opening in contact with said shoulder means; keys disposed in said channels and extending into said opening, the inner ends of said keys engaging said retaining ring; a cover secured to an end of said body and holding said keys in said body; and slips disposed in said opening between said keys, said slips being engaged by said retaining ring and said cover.

4. In a kelly bushing for use in establishing a driving connection between a rotary table and a drill stem, the combination of: a body having a block portion for engagement with said rotary table, there being an opening through said body; shoulder means in said opening, there being an annular channel formed on the inner side of said body in communication with said opening, and there being longitudinal channels formed in said body from said annular channel to one end of said body in communication with said opening; a retaining ring placed in said opening in contact with said shoulder means; keys disposed in said channels and extending into said opening, the inner ends of said keys engaging said retaining ring; a cover secured to an end of said body and holding said keys in said body; and slips disposed in said opening between said keys.

5. In a kelly bushing for use in establishing a driving connection between a rotary table and a drill stem, the combination of: a body having a block portion for engagement with said rotary table, there being an opening through said body; shoulder means in said opening, there being an annular channel formed on the inner side of said body in communication with said opening, and there be-

ing longitudinal channels formed in said body from said annular channel to one end of said body in communication with said opening; a retaining ring placed in said opening in contact with said shoulder means; keys disposed in said channels and extending into said opening, the inner ends of said keys engaging said retaining ring; a cover secured to an end of said body and holding said keys in said body; and slips disposed in said opening between said keys, said slips being engaged by said retaining ring and said cover.

6. In a kelly bushing for use in establishing a driving connection between a rotary table and a drill stem, the combination of: a body having an external formation whereby same may be secured to said rotary table in driving relation thereto, there being an opening through said body; key means extending inwardly from said body into said opening; slip members disposed in said opening between said key means, said slip members providing a passage adapted to receive said drill stem; and means engaging the ends of said slip members for holding same in place in said body.

7. In a kelly bushing for use in establishing a driving connection between a rotary table and a drill stem, the combination of: a body having an external formation whereby same may be secured to said rotary table in driving relation thereto, there being an opening through said body; key means extending inwardly from said body into said opening; slip members disposed in said opening between said key means, said slip members providing a passage adapted to receive said drill stem; and means engaging the ends of said slip members for holding same in place in said body, said means having shoulders for holding said slip members outwardly against said body.

8. In a kelly bushing for use in establishing a driving connection between a rotary table and a drill stem, the combination of: a body having an external formation whereby same may be secured to said rotary table in driving relation thereto, there being an annular opening formed through said body; slip members disposed in said opening and having outer faces for engaging the wall of said body which defines said opening, said slip members providing a passage adapted to receive said drill stem; means cooperating between said body and said slip members for restraining relative rotation between these parts; and means engaging the ends of said slip members for holding same in place in said body.

9. In a kelly bushing for use in establishing a driving connection between a rotary table and a drill stem, the combination of: a body having an external formation whereby same may be secured to said rotary table in driving relation thereto, there being an

annular opening formed through said body; slip members disposed in said opening and having outer faces for engaging the wall of said body which defines said opening, said 5 slip members providing a passage adapted to receive said drill stem; means cooperating between said body and said slip members for restraining relative rotation between these parts; and means engaging the ends of said 10 slip members for holding same in place in said body, said means having shoulders for holding said slip members outwardly against said body.

10. In a kelly bushing for use in establishing a driving connection between a rotary table and a drill stem, the combination of: a 15 body having a formation for driving engagement with a rotary table, there being an opening through said body, and there being a shoulder therein; a plurality of slips in said 20 opening; retaining means in engagement with said shoulder and the lower ends of said slips; and a cover secured to said body and engaging the upper ends of said slips, said 25 retaining means and said cover holding said slips immovably in place.

In testimony whereof, I have hereunto set my hand at Los Angeles, California, this 22 day of March, 1932.

30 WILLIAM D. DAVIDSON.
